UNITED STATES PATENT OFFICE.

POGUE W. FUNSTON, OF CARLYLE, KANSAS.

LOCK AND SEAL.

1,404,593.

Specification of Letters Patent. Patented Jan. 24, 1922.

Application filed July 14, 1920. Serial No. 396,049.

To all whom it may concern:

Be it known that I, POGUE W. FUNSTON, a citizen of the United States, residing at Carlyle, in the county of Allen and State 5 of Kansas, have invented certain new and useful Improvements in Locks and Seals; and I do hereby declare the following to be a full, clear, and exact description of the invention, such as will enable others skilled 10 in the art to which it appertains to make and use the same.

This invention relates to new and useful improvements in locks and seals and has for its primary object the provision of means 15 adapted to fasten a door in a closed position and which cannot be opened without breaking the seal, thereby providing a device especially adaptable for sealing railway cars and other vehicles.

Another object of this invention is the provision of a bolt adapted to receive an endless seal and extends into a keeper and held against retraction until its end is moved beyond the keeper which destroys or 25 mutilates the seal, indicating that the bolt has been retracted or tampered with.

A further object of this invention is the provision of a lock and seal of the above stated character which may be easily and 30 quickly operated and which will be simple, durable and efficient, and which may be manufactured and sold at a comparatively low cost.

With these and other objects in view as 35 will become more apparent as the description proceeds, the invention consists in certain novel features of construction, combination, and arrangement of parts as will be hereinafter more fully described and 40 claimed.

For a complete understanding of my invention, reference is to be had to the following description and accompanying drawing, in which:—

Figure 1 is a view illustrating a lock and seal constructed in accordance with my invention applied to a door frame.

Figure 2 is an enlarged side elevation illustrating the same with the bolt in an 50 unlocked or retracted position.

Figure 3 is a sectional view illustrating the device with the bolt in a locked position.

Figure 4 is a similar view illustrating the 55 bolt moved into a position ready to be re-

tracted and showing the same in a retracted position in dotted lines.

Figure 5 is a detail view taken on line 5—5 of Figure 3.

Figure 6 is a fragmentary perspective 60 view of the locking end of the bolt.

Figure 7 is a perspective view of the seal.

Referring in detail to the drawings, the numeral 1 indicates a base adapted to be secured to a door frame 2 by suitable fastening elements 3 and said base has secured thereto a casing 4 by means of ears 5 that rest on the base 1 and are secured thereto by rivets or like fasteners 6. The end walls of the casing 4 have alining openings 7 to 70 slidably receive a locking bolt 8, one end of which has detachably secured thereto a handle 9. The handle 9 is preferably secured to the locking bolt 8 by means of a pin 10 extending through said handle and 75 bolt and which may be headed so as to prevent the removal of the handle 9 by an unauthorized person. The other end or the locking end of the bolt 8 has a slot 11 which opens outwardly through said end of the 80 bolt for the purpose of receiving a seal 12. The seal 12 is of endless formation and constructed from comparatively thin metal. A rib 13 is also formed on the locking end of the bolt adjacent the slot 11. A substantially U-shaped locking spring 14 is secured to the base 1 within the casing 4 by fastening elements 15 and has its ends disposed in engagement with the bolt 8 and said 85 spring is slightly under tension by being in engagement with the bolt. A locking notch 16 is formed in the bolt 8 within the casing 4 and has a straight shoulder 17 adapted to be engaged by one end of the spring 14 to prevent the bolt from being retracted when 90 said bolt is in one position. The bolt 8 is free for sliding movement in the casing 4 when the notch is disengaged from the spring 14 by turning the bolt 8 within the casing by the handle.

A keeper 18 is formed on one end of the base 1 and is provided with a circular opening 21 to receive the locking end of the bolt 8. A hasp 20 is connected to the door 2 and is adapted to be placed over the keeper prior 105 to inserting the bolt therein. Radially extending slots or notches 22 and 23 are formed in the keeper 18 and communicate with the circular opening 21 and are adapted to receive the rib 13 formed on the locking bolt 110

to prevent rotation or turning movement of the locking bolt when the locking end is disposed, within the keeper.

In operation, the locking bolt 8 is moved 5 into a retracted position with its locking end disengaged from the keeper and the seal 12 is placed in the slot 11 and the handle is turned to the left to aline the rib 13 with the notch or slot 22 of the keeper and said 10 bolt 8 is then moved in the direction of the keeper until its locking end is within the circular opening and the rib in the notch or slot 22 which prevents further rotation of the locking bolt. When the locking bolt is 15 in this position, one end of the spring 14 engages the notch 16 and prevents the bolt from being retracted, thus it will be seen that the door is firmly locked and that the seal cannot be removed without mutilating 20 the same.

To unlock the door, the seal is broken and removed from the slot 11 and the bolt 8 is then pushed further in the direction of the keeper 18 until the rib 13 moves beyond the 25 keeper and out of engagement with the notch or slot 22 then the bolt 18 is rotated by the handle alining the rib with the notch or slot 23 and then the bolt may be retracted as the notch 18 is moved out of the path of 30 the end of the spring 14.

A notch 24 is formed in the bolt 8 within the casing and angularly to the notch 16 and has a straight shoulder which is disposed in an opposite direction from the 35 straight shoulder 17 of the notch 18 and when the bolt is retracted, the notch passes beyond one end of the spring and if through accident the bolt 8 is moved in the direction of the keeper with the rib 13 in alinement 40 with the slot or notch 23, the end of the spring engages the notch 24 or the straight shoulder thereof and prevents further movement of the bolt 8 in the direction of the keeper, thereby obviating any danger of 45 moving the bolt 8 into the keeper with the rib in the wrong notch.

From the foregoing description, taken in connection with the accompanying drawings, it will be noted that the necessity of 50 using tools for joining the ends of seals is

entirely obviated as the railroad company may furnish the various agencies with the endless seals and said seals can be applied to the lock without the employment of a tool as is now customary.

55

While I have shown and described the preferred embodiment of my invention, it will be understood that minor changes in construction, combination, and arrangement of parts may be made without departing 60 from the spirit and scope of the invention as claimed.

Having thus described my invention what I claim is:

1. In a lock, a keeper to receive an article 65 for fastening, a turnable and slidable bolt, said keeper having an opening and notches in communication therewith, a seal applicable to the bolt before extension into the opening of the keeper to limit its projection 70 therethrough, a rib on said bolt to extend into either of the notches, means to hold the bolt against rotation with the rib disposed in one of the notches, said bolt being movable after removal of the seal out of one notch 75 into the other to permit retraction without interference by said means.

2. In a lock, a keeper to receive an article for fastening, a turnable and slidable bolt, said keeper having an opening and notches 80 in communication therewith, a seal applicable to the bolt before extension into the opening of the keeper to limit its projection therethrough, a rib on said bolt to extend into either of the notches, means to hold the 85 bolt against rotation with the rib disposed in one of the notches, said bolt being movable after removal of the seal out of one notch into the other to permit retraction without interference by said means, said 90 bolt having a slot extending inwardly from one end to directly receive the seal, said means consisting of a spring, and the bolt having a notch engageable by said spring.

In testimony whereof I affix my signature 95 in presence of two witnesses.

POGUE W. FUNSTON.

Witnesses:

R. L. THOMPSON,
M. L. WILSON.
